IGNITION APPARATUS

Walter J. Spengler, Sidney, N. Y., assignor to
 Bendix Aviation Corporation, South Bend,
 Ind., a corporation of Delaware

Application July 7, 1942, Serial No. 450,043

16 Claims. (Cl. 171—209)

This invention relates to ignition apparatus and more particularly to supercharged ignition devices and pump means therefor.

One object of the present invention is to provide a novel combination of pump means in a magneto generator to supercharge the casing thereof and particularly the distributor chamber.

Another object is to provide a novel air pump adopted for use in the above combination and having one or more reciprocating pumping members actuated in a novel manner by a rotating member.

A further object is to provide an air pump of the above character with novel means for effecting intake and delivery of the air.

Still another object is to provide a light rugged pump structure which is compact and comprises a small number of readily assembled parts.

A still further object is to provide a novel unitary pump apparatus efficiently operable as a supercharger and adapted to be mounted in a novel manner in a magneto generator or other ignition device so as to be removable as a unit for replacement or repair without impairing the operation of the magneto under normal atmospheric conditions.

The above and further objects and novel features of the invention will more fully appear from the following detailed description when the same is read in connection with the accompanying drawings. It is to be expressly understood, however, that the drawings are for the purpose of illustration only and are not intended as a definition of the limits of the invention, reference for this latter purpose being primarily had to the appended claims.

In the drawing, wherein like reference characters refer to like parts throughout the several views,

Fig. 1 is a view in elevation, with parts broken away and shown in section, of one form of magneto embodying the present invention; and

Fig. 2 is a sectional view taken substantially along line 2—2 of Fig. 1.

The invention is illustrated in the drawings, by way of example, in the form of a novel pump mounted within a casing of a magneto adapted for use in the ignition system of an internal combustion engine. In the form shown, the pump means is driven by the ignition distributor shaft and is adapted to deliver air under pressure to the distributor chamber of the magneto. By thus maintaining the air within the distributor chamber under pressure, danger of undesirable arcing

within said chamber and, hence, failure of the ignition system at high altitudes are substantially eliminated.

One form of the pump means of the present invention is shown operatively mounted for supercharging the distributor chamber 10 of a magneto generator 11 of the type disclosed in my Patent No. 2,104,140. It is to be understood that the pump may also be utilized, for example, for supercharging the entire magneto interior or compartments thereof other than the distributor chamber and may be embodied in other types of apparatus wherein supercharging is desired.

As shown in Fig. 1, a wall 12 of the magneto housing constitutes one wall of chamber 10, while a distributor and contact block 13 mounted in said housing and laterally spaced relative to wall 12 forms the opposite wall of said chamber. At the lower end of the chamber, member 14, which may be of insulating material, is secured to wall 12, for example, by screws 14a, and engages the lower end of block 13 to seal and insulate chamber 10 from a compartment 15 which contains magneto rotor 16. For the purpose of reducing leakage from chamber 10 so that air under pressure might be maintained therein or, if desired, to render said chamber substantially air or fluid-tight, the parts comprising the walls thereof are carefully fitted together to produce substantially air-tight junctions therebetween. However, to further insure against excessive leakage of air, it may be desirable to employ gaskets or apply a suitable sealing composition having a high melting point, such as hydrolene wax at the engaging surfaces of the parts.

Mounted in wall 12 is a bearing 17 which journals a hollow distributor drive shaft 18 having a flange 19 formed therewith, said flange having a distributor rotor 20 suitably attached thereto, for example, by screws 21. Sockets 21a are preferably molded in said rotor to receive screws 21 and each of said sockets preferably projects beyond the face of the rotor so that an air gap 21b is provided between said rotor and the flanged end of shaft 18. Rotor 20 carries a central contact 22 and a contact 23 near the periphery which are connected to each other, the former engaging a current supply contact 24 in insulating block 13 and the latter cooperating in a manner well understood in the art with a plurality of circularly arranged contacts 25 mounted in said block adjacent the periphery thereof. These parts operate in a manner well-known in the art to distribute high tension current from

the secondary winding of the magneto coil to the engine spark plugs.

The left-hand end of shaft 18, as viewed in Fig. 1, projects beyond wall 12 and a gear wheel 26 is keyed or otherwise fixed to the projecting portion of said shaft, said gear wheel being in driving mesh with a gear on rotor shaft 16. These driving means are enclosed in a compartment 27 formed by a cup-shaped cover 28 which is secured to wall 12 and forms a part of the magneto housing. A portion of shaft 18 adjacent flange 19 has a close running fit with a portion 12a of wall 12 to minimize any leakage of air from chamber 10 so that the latter may be substantially air-tight.

In order to maintain the pressure of the atmosphere in chamber 10 above atmospheric pressure outside of said chamber, means are mounted in magneto 11 for compressing air admitted thereto from outside the magneto and discharging the compressed air into said chamber. As shown, said means comprise a cylindrical casing 30 open at one end and provided with an external flange 31 at the other end whereby said casing is secured in cover 28, for example, by screws 32, with the open end thereof extending into compartment 27. Cylindrical casing 30 thus completes and may be considered as a part of the enclosing housing for the illustrated ignition apparatus. The central axis of the cylindrical wall 30a of casing 30 is eccentric with respect to the axis of hollow distributor shaft 18 and a stationary stub shaft 33 is rigidly secured to the casing, preferably by being formed integrally therewith, said stub shaft being coaxial with and extending into the interior of said distributor shaft. Wall 30a is thus eccentrically disposed relative to said stub shaft which, as will hereafter appear, constitutes means for connecting the enclosing housing with the atmosphere outside the latter.

Journalized on shaft 33 for rotation relative thereto is a pump rotor 34 of novel pressure increasing means located within housing 30, said rotor having a sleeve 35 formed therewith that extends into shaft 18 and is drivably connected to the latter shaft for rotation therewith by any suitable means, such as by cooperating splines. Rotor 34 is provided with one or more radial, cylindrical bores or recesses 36, two being shown in the present embodiment, each of which is adapted to receive a cylindrical plunger or piston 37, the latter preferably having the outer end thereof rounded for smooth engagement with the internal periphery of wall 30a. The inner end of each of said bores terminates a short distance from the inner wall of rotor 34 and a passage or port 38 (Fig. 2) connects each of the bore interiors to the central recess of said rotor which receives extension or journal 33. The latter is provided with a central axial intake passage 39 which communicates at one end with the magneto exterior and at the other end, by means of an angularly disposed portion 39a, with the periphery of journal 33. The open end of portion 39a of said passage is located in the same transverse plane as each of ports 38 and subtends a substantial angular distance around said shaft, preferably about 90°, so that each of ports 38 is in communication with intake passage 39 for approximately one-fourth of each revolution of rotor 34. A central axial discharge passage 40 is also provided in journal shaft 33 and connects at one end with the interior of shaft 18 and at the other end, by means of an angularly dis-

posed portion 40a, with the periphery of shaft 33, the end of said portion being located in the same transverse plane as ports 38 in order to successively overlap the latter during each revolution of rotor 34.

In operation, rotation of rotor 34 in a counter-clockwise direction, as viewed in Fig. 2, causes plungers 37 to move radially outward in response to centrifugal force into engagement with the internal periphery of casing wall 30a, the eccentricity of which causes reciprocation of said plungers in bores 36. When port 38 connects with intake passage 39 during rotation of said rotor, air intake at atmospheric pressure begins and continues until passage 39 moves beyond port 38. Passage 39 preferably has portion 39a thereof so located relative to housing wall 30a that air intake begins as the plunger 37 is moving outwardly in bore 36 and is substantially at its outermost or bottom dead center position, thereby permitting a maximum volume of air to be admitted into bore 36. The lower piston, as shown in Fig. 2, is at its outermost position and intake has just ceased. Compression begins when port 38 moves out of communication with passage 39 and continues until said port overlaps discharge passage 40, at which point piston 37 is substantially at its top dead center or innermost position, having effected a maximum compression of the air which is then discharged into chamber 10 through passages 40, 40a and shaft 18. This cycle of operations is repeated by each plunger 37 during every revolution of rotor 34, thereby maintaining relatively continuous flow of air under pressure into chamber 10.

It is to be noted that the novel pump means, as shown, comprise only three movable parts, all of which are relatively simple in design and construction, and that the pump can be removed from its housing without affecting the connection between distributor rotor 20 and the drive means therefor and without altering the normal operation of the magneto except for the supercharging of chamber 10. If desired, light springs may be used to assist centrifugal action in moving plungers 37 outwardly.

There is thus provided a novel combination of parts wherein means are mounted in the casing of an ignition device and driven thereby to supercharge the interior of said casing. There is also provided novel pump means adapted for supercharging the distributor chamber of a magneto generator, said pump being compact, positive in operation and comprising a minimum of moving parts. A novel arrangement for mounting said pump in the magneto in relation to the distributor rotor and the drive means for said rotor is also provided as well as novel means for controlling the air intake and discharge of the pump.

Although only a single embodiment of the invention has been illustrated and described, it is to be expressly understood that the same is not limited thereto. For example, it will now be apparent to those skilled in the art that three or more equally spaced bores containing plungers therein could be used instead of the two illustrated. Various other changes may also be made in the design and arrangement of parts illustrated without departing from the spirit and scope of the invention. For a definition of the limits of the invention, reference is had primarily to the appended claims.

What is claimed is:

1. In an ignition device, a casing and means for supercharging said casing comprising a cyl-

drical housing mounted in said casing, a rotor eccentrically mounted in said housing, said rotor having at least one radial bore, a plunger slidably mounted in said bore and having its outer end extending from said rotor for engagement with said housing, said plunger being reciprocated in said bore by rotary movement of said rotor and forming a compression chamber with the walls of said bore, a port communicating with said chamber, and stationary means for mounting said rotor, said means having air intake and discharge passages, said intake passage connecting with said port just before and until said plunger reaches its bottom dead center position and said discharge passage connecting with said port when said plunger is approximately at top dead center position.

2. In a magneto having a housing and a substantially fluid-tight chamber in said housing containing an ignition distributor, a drive shaft for the rotatable part of said distributor, a pump mounted in said housing and drivably connected to said shaft, and means controlling the air intake and discharge of said pump, said last-named means comprising an air intake passage communicating with the housing exterior and a discharge passage connecting with said chamber through an axial passage in said shaft.

3. In a magneto having a housing and a substantially air-tight chamber in said housing containing a distributor, a drive member directly connected to the rotary element of said distributor, an air pump mounted in said housing and having a movable part thereof directly connected to said drive member, and means controlling the air intake and discharge of said pump, said means comprising an intake passage communicating with the housing exterior and a discharge passage connecting with said chamber.

4. In pump apparatus adapted for supercharging an ignition device, means forming a compression chamber, including a reciprocating plunger, a cylindrical casing eccentrically surrounding said means, said plunger engaging said casing, drive means for rotating said first-named means whereby said plunger is reciprocated, and means including a plurality of passages for controlling the intake and discharge of said compression chamber.

5. In apparatus of the class described, a housing, a member eccentrically mounted relative to said housing and having a radial bore therein, a plunger slidably mounted in said bore and having its outer end adapted for engagement with said housing in such a manner that relative rotation between said member and said housing reciprocates said plunger, and means connecting with said bore and adapted to control the admission of air thereto and discharge of air therefrom.

6. Pumping means comprising a rotary member, at least one centrifugally responsive plunger slidably mounted in said member to effect air compression when reciprocated, a housing eccentrically disposed relative to said member and adapted to engage said plunger, and means for effecting rotation of said member relative to said housing to cause reciprocation of said plunger.

7. In a magneto having a substantially fluid-tight chamber, a distributor in said chamber and drive means extending through the wall of said chamber for connection with the rotor of said distributor, the combination with said drive means of a pump connected to said drive means and actuated thereby, said pump being disposed on the exterior of said chamber and discharging air

under pressure into said chamber through a passage in said drive means.

5 8. In a magneto having a housing and a substantially fluid-tight chamber in said housing containing an ignition distributor, a drive shaft for the rotor of said distributor, and pump means mounted in said housing on the exterior of said chamber and operatively connected to said shaft to be driven thereby, said pump means discharging air under pressure into said chamber.

15 9. In a magneto having a substantially fluid-tight chamber containing a distributor, drive means including a hollow shaft for said distributor and a supercharger pump connected to said shaft to be actuated thereby, said supercharger pump discharging air under pressure into said chamber through said hollow shaft.

20 10. In apparatus of the class described, a substantially fluid-tight chamber, a distributor rotor in said chamber, a hollow drive shaft extending through the wall of said chamber and connected at one end thereof to said distributor rotor, a pump rotor connected to the other end of said shaft, plunger means in said pump rotor for compressing air, an eccentric surrounding said pump rotor and adapted to engage and actuate said plunger means, and a member rigidly secured to said eccentric and extending centrally through said pump rotor as a journal therefor, said member having an inlet passage for directing air to said plunger means for compression and a discharge passage for directing the compressed air from said plunger means to the interior of said shaft.

25 35 11. In apparatus of the class described, a housing having a substantially fluid-tight chamber, a distributor rotor in said chamber, a hollow drive shaft extending through the wall of said chamber and connected at one end thereof to said distributor rotor, a pump rotor connected to the other end of said shaft, plunger means in said pump rotor for compressing air, an eccentric surrounding said pump rotor and adapted to engage and actuate said plunger means, and means for directing air to said plunger means for compression and for directing the compressed air from said plunger means to said chamber.

40 50 12. In apparatus of the class described, a housing having a relatively fluid-tight chamber, a driven member in said chamber, drive means extending through the wall of said chamber and connecting at one end with said driven member, a pump rotor connected at the other end of said shaft, plunger means in said pump for compressing air, an eccentric surrounding said pump rotor and adapted to engage and actuate said plunger means, and means for directing air to said plunger means for compression and for directing the compressed air from said plunger means to said chamber.

55 60 13. An electric ignition apparatus for an airplane which is adapted to fly in rarified atmospheres including a substantially air-tight enclosing casing for said ignition apparatus, means for connecting said enclosing casing with atmosphere outside said enclosing casing, and pressure increasing means within said enclosing casing, said pressure increasing means having its intake side in connection with said communicating means so that upon actuation of said pressure increasing means said apparatus within said casing will be supercharged to a pressure substantially higher than the pressure of atmosphere outside said casing.

70 75 14. An electric ignition apparatus for an air-

plane which is adapted to fly in rarified atmospheres including a magneto, a distributor, a substantially air-tight enclosing casing for said distributor, means for connecting said enclosing casing with atmosphere outside said enclosing casing, and pressure increasing means within said enclosing casing, said pressure increasing means having its intake side in connection with said communicating means so that upon actuation of said pressure increasing means said apparatus within said casing will be supercharged to a pressure substantially higher than that of the atmosphere outside said casing.

15. An ignition device including a rotatable shaft, a substantially air-tight enclosing casing for said device, a port in said casing, pressure increasing means within said enclosing casing, said pressure increasing means having its intake side in substantially air-tight communication with

said port, and means for actuating said pressure increasing means from said shaft so that upon rotation thereof the pressure within said device enclosing casing will be built up to a value substantially higher than the pressure outside said enclosing casing.

16. A magneto distributor device including a rotatable shaft, a substantially air-tight enclosing casing for said device, a port in said casing, pressure increasing means within said enclosing casing, said pressure increasing means having its intake side in substantially air-tight communication with said port, and means for actuating said pressure increasing means through said shaft so that upon rotation thereof the pressure within said device enclosing casing will be built up to a value substantially higher than the pressure outside said enclosing casing.

WALTER J. SPENGLER.
